UNITED STATES PATENT OFFICE.

LEO TURK, OF EAST YOUNGSTOWN, OHIO.

DOOR-LOCK MECHANISM.

1,141,590.

Specification of Letters Patent.

Patented June 1, 1915.

Application filed December 26, 1914. Serial No. 879,101.

To all whom it may concern:

Be it known that I, LEO TURK, subject of the King of Hungary, residing at East Youngstown, in the county of Mahoning and State of Ohio, have invented certain new and useful Improvements in Door-Lock Mechanism, of which the following is a specification.

This invention relates to certain new and useful improvements in door lock mechanism.

It will first be noted that the present lock is primarily designed for employment upon either an outer or an inner door and has 15 separate means arranged upon the inner side of the door for actuating the lock mechanism which is distinct and independent from the actuating means arranged upon the outside of the door.

20 One of the objects of the invention is to provide the inner side of the door with merely a latch and knob for the complete control of the lock bolt, there being no key-hole opening at the inner side of the door 25 and the lock being therefore controlled from the inner side without the employment of a key.

The main object however of the invention is to provide a lock mechanism in which the 30 bolt is automatically projected in its locked position upon closing the door and is released for withdrawal by the outer knob by means of two independent push buttons arranged at the outside of the door, it being 35 necessary to successively press each of the said buttons a predetermined different number of times for the purpose of positioning the lock mechanism so as to allow such retraction of the bolt. Coupled with this object of the device is a means shiftable from the edge of the door whereby the combination of the push buttons may be changed as 40 desired or in other words the number of impulses required to be exerted upon such push button may be predetermined all of which 45 inures to make the lock a serviceable safety device and difficult to manipulate by any unauthorized person. This object also includes a key manipulated means operable only 50 from the outside of the door for rendering the push button releasing means either active or inactive at will, while combining with such, a key-hole spindle of substantially the same external appearance as the 55 push buttons and adapted for being manually depressed for automatically allowing

the shifting of the bolt engaging lock mechanism from the unlocked to the locked position.

While the outer and inner knobs are independently operable for shifting the bolt when released by the lock mechanism, the latch on the inner side of the door is operable for locking the bolt against withdrawal from either side of the door when in 60 one position leaving the bolt entirely free to be moved by either knob when in another position and rendering the bolt retractable only by the inner knob when in a still further position.

It is also designed to provide means whereby the desired one of the push buttons must be completely operated before the other push button begins its work so that a person must be familiar with this feature 70 of the mechanism for the perfect operation of the lock, while it is also provided that both of the bolt locking members may be returned to their normal locked position by depressing the key-hole spindle in the event 75 that an unsuccessful manipulation of the buttons has been made in order to allow the operator to successfully renew his endeavors to correctly operate the buttons in accord with the predetermined combination. 85

With these general objects in view and others that will appear as the nature of the invention is better understood, the same consists in the novel combination and arrangement of parts hereinafter more fully 90 described, illustrated in the accompanying drawings and set forth in the appended claims.

In the drawings forming a part of this application and in which like-designating 95 characters refer to corresponding parts throughout the several views, Figure 1 is a front elevation of a portion of the outer side of a door provided with the present invention. Fig. 2 is a similar view of the inner 100 side of the door. Fig. 3 is a similar view of the edge of the door. Fig. 4 is a perspective view of the outside door plate detached. Fig. 5 is a similar view of the edge plate of the door detached. Fig. 6 is a perspective view of the lock casing partially 105 broken away and with the edge plate secured thereto, but with the lock mechanism and the outer side plate of the casing removed. Fig. 7 is an elevational view of the inner knob and the two-part shank with the separate ward members arranged upon the shank.

Fig. 8 is a view similar to Fig. 7 partially broken away and with the ward members removed from the shank. Fig. 9 is a perspective view of the two ward members detached from the knob shank, but arranged in the same order as positioned thereon in Fig. 7. Fig. 10 is a perspective view of the automatic bolt engaging catch for the door edge portion of the lock. Fig. 11 is a perspective view of the limiting stop for the bolt locking members detached. Fig. 12 is a perspective view of the key actuated members separated and detached. Fig. 13 is a perspective view of the latch actuated bolt stop. Fig. 14 is a plan view of the lock mechanism with the outer plate of the casing and the lock bolt with its spring removed therefrom. Fig. 15 is a similar view with one of the push button operated shifters partially actuated and showing the locking bolt with its spring in position as well as the depressible key-hole spindle. Fig. 16 is a view similar to Fig. 15 but with the bolt projected and the key-hole spindle removed and showing one of the shifters as positioned at the end of its operative stroke. Fig. 17 is a transverse sectional view through the casing upon a plane slightly removed from the edge plate. Fig. 18 is a detail sectional view through the key spindle collar. Fig. 19 is a perspective view of the toothed wheel employed with the combination changing stop. Fig. 20 is a perspective view of the inner face of the end of the casing engageable by the wheel shown in Fig. 19. Fig. 21 is a detail sectional view through the casing and the knob shank wards shown in their operative positions. Fig. 22 is a sectional view upon a plane at right-angles 40 along a line of section of Fig. 21 and showing the said wards in elevation. Fig. 23 is a perspective view of the lock bolt detached. Fig. 24 is a perspective view taken from the opposite side of the lock bolt from that shown in Fig. 23. Fig. 25 is a perspective view of the inner face of the outer side plate of the lock casing detached. Figs. 26 and 27 are perspective views of the outer narrower and the inner broader coöperating bolt locking members respectively detached and separated from each other. Figs. 28 and 29 are perspective views of the push button actuated shifters for the said outer and inner bolt locking members respectively. Fig. 30 is a perspective view of the spring dog mechanism detached for the bolt locking members. Fig. 31 is a perspective view of the latch moved actuator detached. Fig. 32 is a perspective view of the mounting bracket for the actuator shown in Fig. 31, and Fig. 33 is a side elevation of one of the pivoted engaging hooks carried by the bolt.

This invention being designed for use 65 upon a door, the same is illustrated in con-

nexion with a door 10 and has the lock casing 11 countersunk within the edge 12 of the door while the front side or wall 13 of the casing has the edge plate 14 of the door secured thereto.

The lock is provided on the inside of the door with a turn knob 15 and also with a swinging latch 16 both operable as herein-after described while on the outer side of the door a similar knob 17 is provided which has entirely independent movement from the inner knob, a key-hole spindle 18 and upper and lower push buttons 19 and 20 being also found upon the outer side of the door. The usual door plates 21 and 22 are arranged respectively upon the inner and outer sides of the door.

A longitudinal shiftable bolt 23 is mounted within the casing 11 and has its forward end portion 24 which is rectangular in cross-section adapted to project through the alining openings 25 and 26 respectively, in the front wall of the casing and the edge plate. A spring catch 27 is secured at one end to a post 28 adjacent the said casing wall 13 and has a reduced angularly-projecting free end 29 that is adapted to seat within a transverse corner socket 30 of the adjacently-positioned bolt portion 24. A detent 31 substantially of triangular form is pivotally mounted through alining slots 32 and 33 respectively, in the said front wall and edge plate by means of trunnions 34 upon the said detent which are journaled in the said front wall in opposite sides of the slot 32 thereof. By this arrangement it will be seen that when the bolt is retracted, the catch 27 will automatically drop within the socket 30 while the bolt is readily released by an inward pressure exerted upon the detent 31. A coil spring 35 is mounted upon a post 36 within the casing and has one end thereof secured to the post while the opposite end of the spring engages the inner end of the bolt within the angular notch 37 thereof, it being noted that a retracting of the bolt places the spring under tension so that when the bolt is released by the catch 27, the said spring 35 automatically projects the bolt to its locked position.

Within the lock casing, two overlying bolt locking members 38 and 39 (see Figs. 26 and 27) are provided transversely shiftable beneath the bolt 23, the locking member 39 lying undermost and provided with teeth 40 upon one edge thereof and with a perpendicularly projecting flange 41 adjacent its opposite edge, which flange has an inwardly projecting guard 42 and is also provided with a notch 43 adjacent the said guard and in direct alinement with a pre-determined one of the teeth 40. The locking member 38 is positioned outwardly upon the inner locking member 39 being narrower than the said member 39 and being provided with 130

teeth 44 upon one edge corresponding to the teeth 40 upon the member 39, it being understood that the edge of the member 38 opposite to the toothed edge thereof is slidably positioned beneath the aforementioned guard 42. A perpendicularly positioned flange 45 is longitudinally arranged upon the outer locking member 38 and is provided with a notch 46 of a width corresponding to the length of one of the teeth 44 which notches 46 and 43 are required to be positioned in direct alinement for releasing the bolt 23 when the same is projected and by means of the mechanism hereinafter set forth. The two locking members 38 and 39 being thus assembled, are together slidably mounted upon the inner wall 47 of the casing and within the same while the line of movement thereof transversely beneath the bolt 23 is directed by means of perpendicularly arranged guards 48, 49 and 50 upon the said casing wall 47. The outer locking member 38 has a projecting finger 51 at one end thereof adjacent the toothed edge 44 and to which finger a coil spring 52 is attached for normally retaining the said locking member in its locked position as best illustrated in Fig. 14, it being noted that the other end of the spring 52 is anchored as at 53. The inner locking member 39 has a similar finger 54 at the corresponding end thereof adjacent the flange 41 and to which finger 54, one end of a spring 55 is secured while the opposite end of said spring is anchored to the casing as at 56 such arrangement normally tending to maintain said inner locking member in its locked position with respect to the bolt.

It will thus be seen that the members 38 and 39 are transversely shiftable beneath the bolt 23 and it will be noted that the said bolt is provided with two similar double hooks 57 having pivoting trunnions 58 whereby the hooks are shiftably mounted within two similar slots 59 arranged in longitudinal alinement slightly spaced apart longitudinally of the said bolt, while similar springs 60 are provided for each of the said hooks for normally retaining the opposite claws 61 and 62 projecting outwardly of the opposite sides of the said slots. The claws 62 project from the inner side of the bolt, or in other words, protrude through the slots 59 upon that side of the bolt which is adjacent to the locking members 38 and 39, such protrusion of the hooks being sufficient to lie within the paths of movement of the flanges 41 and 45 of the locking members and as will be evident, when such claws are so projecting, being positioned away from the center of the lock casing from the said flanges 41 and 45, the bolt will be thereby restrained when projected from being retracted until either the said claws 62 are withdrawn so as to allow the same to pass

over the flanges 41 and 45 or unless the notches 43 and 46 of the locking members are brought into alinement with each other and also with such claws 62 and so that the claws will be relieved from their engagements with the said flanges and will freely pass through the said notches thereof in the bolt-projecting movement.

The inner knob 15 has a squared shank 63 upon which a ward 64 is secured, being at all times positioned within a recess 65 of one edge of the bolt 23 and being also positioned within a notch 66 of a shiftable plate 67 that is slidably mounted upon the under face 68 of the bolt while the notch 66 is of less dimensions than the recess 65, which allows the plate 67 to be shifted longitudinally upon the bolt by means of the knob ward 64 when the bolt is held stationary. The said plate 67 is provided with two slots 69 normally positioned in alinement with the bolt slots 59 through which plate slots the engaging claws 62 project. It will thus be seen that when the bolt is projected and the claws 62 retain the same in its locked position, a shifting of the plate 67 for depressing the claws 62 releases the bolt. When so released, the further turning of the inner knob engages its ward 64 with the adjacent edge of the recess 65 and thus retracts the bolt.

The outer knob 17 has a squared shank 70 while the inner adjacent ends of the two knob shanks 63 and 70 are freely journaled together as at 71. The outer knob shank is provided with a ward 72 secured thereon which projects within the said recess 65 of the bolt so that whenever the bolt is free to move longitudinally, the outer knob 17 may manually operate the same.

The latch 16 upon the inner side of the door is provided with a squared shank 73 projecting within the casing and having a collar 74 secured thereon which is provided with a projecting lug 75. The said inner latch is adapted to completely lock the bolt by means of a slideable bolt stop 76 of the form illustrated in Fig. 13 and which stop is slidably mounted within the casing by means of pins 77 carried by the casing which are received within a longitudinal slot 78 of the said stop. The inner end of the stop is provided with a flange 79 which may be positioned rearwardly and inwardly of a projecting lug 80 carried by the bolt on the adjacent side thereof while an end finger 81 upon the said flange is engageable by the latch lug 75 for moving the stop 76 to the position shown in Fig. 14 which will be out of the retracting path of travel of the bolt. While the position of the stop flange as illustrated in Fig. 14 is such as to allow a retracting of the bolt, the latch may be turned for engaging the lug 75 with the curved shoulder 82 of the stop and thus

moving the stop to the dotted line position illustrated in Fig. 14, at which time the lug 80 will engage the flange 79 upon any attempt to withdraw the bolt by either the 5 outer or inner knob.

A shiftable side plate 83 is arranged upon the outer side of the bolt similar to the inner slide plate 67 and has slots 84 therein adapted to normally align with the bolt slots 59 10 so that the claws 61 project through the plate slots 84 when the opposite claws 62 are projected in their engaging positions. An arm 85 is secured to the plate 83 and is bent around the bolt and projects between parallel fingers 86 carried by a latch moved actuator 87 of the form illustrated in Fig. 31, which actuator is pivoted as at 88 to a stationary bracket 89 within the casing. The said actuator has a segment-shaped socket 20 90 within which the latch lug 75 is adapted to engage for turning the actuator and thereby shifting the arm 85 as well as the plate 83 when the bolt is held stationary, a lug stop 146 being provided for the lug 75. It 25 will be evident that a shifting of such plate 83 over the projecting claws 61 will depress the same within their respective slots, and which action will also retract the flange-engaging bolt retaining claws 62. The latch 30 16 therefore is adapted when properly manipulated to turn such actuator to render the claws 62 entirely inoperative, so that the bolt is free to be retracted by turning either the outer or the inner knob.

35 From the above description it will be seen that when the latch 16 is positioned at one extreme of its movement, the actuator 87 will be positioned as illustrated in Figs. 14 and 15 with the bolt freely shiftable by either 40 knob while the other extreme movement of said latch outwardly moves the stop 76 to the dotted line position shown in Fig. 14, at which time the bolt is restrained against movement by either of the knobs while an intermediate positioning of the latch shifts 45 the stop 76 inwardly and leaves the actuator 87 in such a position as to place the plate 83 so as to unobstruct the claws 61, whereby the outer knob will be capable of retracting the 50 same through the agency of its ward 64 first moving the releasing plate 67 for retracting the engaging claws 62.

Separate shifters 91 and 92 (see Figs. 28 and 29) are provided respectively, for the 55 outer and inner locking members 38 and 39, the said shifters being arranged shiftable mounted overlying each other and each having similar sharpened top fingers 93 which are adapted to forcibly engage the teeth 44 and 40 of the locking members for inwardly shifting such members. These shifters are 60 slidably positioned within a housing 94 and each is provided with a similar retractile spring 95 for normally retaining the shifters 65 within the housing. Laterally projecting

arms 96 and 97 are carried by the outer and inner shifters respectively, and the same are adapted to be operatively engaged by the inner ends 98 and 99 respectively, of the upper and lower rockers 100 and 101 pivoted 70 to the inner side of an outer side plate 102 of the lock casing. The upper and lower push buttons 19 and 20 are provided with inwardly projecting fingers 103 which are constantly seated upon the adjacent ends 104 and 105 respectively, of the said upper and lower rockers. Separate dogs 106 and 107 are respectively provided for the teeth 44 and 40 of the shiftable locking members while such dogs are pivoted to one end of a lever 108 by means of a pivot pin 109 and by means of which pin also the lever is pivoted to the casing wall 47, it being noted that each of the said dogs is provided with a similar spring 110 mounted upon the said lever and adapted to hold the dogs at one extreme of their movement and as limited by the free end 111 of the said lever. A blade-shaped plate 112 has a corner portion thereof secured to the free end of the said lever while the flattened face of the plate is engaged by similar leaf springs 113 carried by each of the shifters 91 and 92 whereby the lever is normally positioned to place the dogs in engagement with their respective teeth of the locking members while such members are capable of inward movement toward their releasing positions by a ratcheting movement of the teeth beneath the said dogs and their resilient retractions as permitted by the 80 aforementioned springs 110.

The key-hole spindle 18 projects within a tubular collar 114 and is provided with a side lug 115 slidable within a side slot 116 of the said collar 114 while the said spindle 105 is normally maintained projected by means of a coil spring 117 mounted inwardly thereof within the said collar, it being noted that the spindle has a terminal projecting barrel 118 projecting through an opening 119 in the casing wall 47 positioned centrally of the said collar. This arrangement positions the lug 115 as illustrated in Fig. 18 with respect to the plate 112 so that by depressing the spindle 18, the lug 115 engages the said plate and moves the same in a direction away from the said spindle, thus rocking the lever upon its pivot pin 109 and releasing the dogs from the teeth of the locking members. The dog 106 of the outer locking member is provided with an inwardly projecting lug 120 which engages the companion dog 107 so that whenever the dog 106 is actuated, the dog 107 must move therewith, but on the contrary, any movement of the dog 107 will not influence the dog 106 for movement.

A bracket 121 is positioned adjacent the collar 116 and has a slide 122 mounted therein to which a hook 123 is pivoted for 130

retaining the slide at one limit of its longitudinal movement, there being also provided a spring 124 carried by the bracket 121 and engaging the said hook which automatically 5 engages the hook with a pin 125 of the casing whenever the slide has reached such limit of its travel. A key member (not shown) is adapted to move the slide by engaging a lateral projection 126 of the slide 10 by which such projection is forcibly moved against the plate 112 for completely releasing the dogs from their engagement with the teeth of the locking members, and this being the limit of the movement of the 15 slide, the hook automatically engages the pin 125 for so retaining the slide until the key is turned in an opposite direction which engages the heel 127 of the hook and releases the hook, after which the key engages 20 the shoulder 128 of the slide and moves the latter to its inoperative position and other extreme movement.

The bolt is provided with a longitudinal slot 129 at the opposite end thereof from the locking end 24 and a post 130 of the aforementioned bracket 89 is positioned within the said slot 129 for giving direction to the path of movement of the bolt. A spring 131 is carried by the bolt face 69 and engages 25 the sliding plate 67 to normally retain the said plate out of contact with the claws 62. The outer plate 102 of the casing is adapted 30 to be secured within notches 132 of the opposite side walls of the casing.

35 The bolt is provided with a triangular lug 133 upon one edge thereof which normally engages the plate 112 when the bolt is retracted and thereby holds the dogs out of engagement with the teeth of the locking members so that their respective return 40 springs normally retain the locking members in their operative position for being automatically engaged by both bolt claws 62 whenever the bolt is projected by pressing the detent 31. It will thus be noted that 45 when the detent is so pressed, the spring 35 automatically projects the bolt to its locking position and the bolt locking members being normally positioned as shown in Fig. 50. 14, the said claws will engage behind the flanges 41 and 45 of the locking members and will prevent a retracting of the bolt, the outward movement of the bolt being limited by the stop shoulder 145 upon the 55 bolt.

When the bolt is projected, it is retractable without moving the locking members 38 and 39 to their releasing positions by shifting either of the side plates 83 or 67 by means 60 of the latch or inner knob respectively, in the manner hereinbefore described.

In the manipulation of the lock from the outer side of the door, the push buttons 19 and 20 are employed and it is necessary to 65 manipulate each of said buttons a sufficient

number of times to inwardly project the locking members respectively influenced thereby, so as to position the flange notches 43 and 46 of such members in direct alignment with each other and with the engaging 70 claws 62 of the bolt. It will be noted that each impress upon either of the push buttons moves its corresponding locking member inwardly a distance corresponding to one of its teeth and such teeth being of a 75 length equal to the width of the flange notch of that member, it will be seen that the required distance for moving each of the locking members may be readily ascertained and consequently the number of impulses 80 which must be given to each of the push buttons is accurately determined for the purpose of releasing the bolt from the locking members. It will be seen in the present instance, that the notch 46 of the outer locking 85 member is separated a distance of three teeth from the position of the flange notch 43 of the other locking member when both locking members are normally positioned so that in the event that it requires eight impulses upon the button 19 to place the notch 46 in alignment with the bolt claws 62, it will necessarily require five impulses upon the button 20 to accurately position the notch 43 of the inner locking member so as 90 to render the bolt freely retractable through the notches of the said members. It is thus necessary for a person to know the correct combination in order to manipulate the locking members for releasing the bolt and for 95 further limiting the chance of unauthorized manipulation, the aforementioned lug 120 is provided upon the outer locking member dog 106 so that the outer locking member 100 dog 106 must be first completely moved to its releasing position by its push button 19 before the inner locking member begins its longitudinal movement under the influence of its push button 20. This is for the obvious reason 105 that if the inner locking member was moved longitudinally prior to the movement of the outer member 38, any subsequent impulse given to the push button 19 of such outer member would move the dog 106 of the outer member, which would thereby release the 110 dog 107 of the inner member for allowing the inner member to automatically return to its normal locked position. As an unauthorized person might infer that each of the 115 two push buttons is alternately manipulated, it will be seen that this requirement for the complete actuation of the upper push button prior to that of the lower button makes the locking mechanism more complete. 120

In the event that one or more of the push buttons is actuated but for some reason the bolt is not retractable, such for instance, as an error on the part of the operator in giving the proper number of impulses, the spin- 125 130

dle 18 may then be depressed which will automatically release both of the dogs and thus return both of the locking members to their locked positions and allow the operator to start anew upon the manipulation of the proper combination.

It will be also noted that when the bolt locking members are positioned for releasing the bolt, either of the knobs may be turned for retracting the bolt against the action of the spring 35 and so as to allow the bolt catch 27 to automatically retain the bolt in its released position, while the aforementioned lug 133 will engage and depress the plate 112 during such inward movement of the bolt and this automatically releases the dogs for allowing the bolt locking members 38 and 39 to automatically return to their operative positions while as before noted, the lug 133 will then remain in depressing contact with the said plate until the bolt is again projected. It will also be seen that whenever the door is closed, at which time of course the bolt is retracted, the outer edge of the detent 31 will engage the door casing for automatically releasing the bolt catch and thus allowing the bolt to be automatically projected to its locked position.

It is desirable to provide a means for changing the combination for the actuation of the push buttons and this is herein illustrated as consisting of a toothed rack 134 which has a foot 135 positioned within the path of movement of the bolt locking members so that the position of such foot determines the normal locked position of the said members. A pinion 136 is carried by the inner end of a screw 137, which pinion is in constant mesh with the teeth of the rack 134 while the said screw is provided with a kerf 138 in the head thereof countersunk in the edge plate 14 so that the screw may be readily controlled by means of a proper implement for moving the rack and changing the position of the limiting foot, a guard flange 147 being provided for the rack. The pinion is provided with a projecting lug 139 on its inner face which is adapted to engage the grooves 140 upon the adjacent face of the casing wall 13 so that the pinion and rack will remain in the desired adjusted positions to accurately place the locking members in proper relation respecting their shifters 91 and 92. A spring 144 is carried by the inner end 143 of the screw 137 which insures a seating of the lug within one of the said engaging grooves. A radial mark 141 is positioned on the head end of the screw adjacent the kerf 138 and which mark is adapted to be brought into registry with different ones of the numerals 142 arranged upon the edge plate so that the condition of the combination changing device may be readily ascertained by the authorized operator of the lock.

From this detailed description of the device, it will be readily seen that the desired positioning of the lock mechanism is readily carried out from the inside of the door by means of the latch and without the necessity of a key and whereby the bolt is rendered inoperative by either knob, capable of being operated by the inner knob alone or readily actuated by either the outer or inner knob.

As also specifically described, it will be seen that from the outer side of the door the push buttons may be readily actuated by a person familiar with the lock, whereby the bolt is released from the locking members so that the outer knob may be turned for retracting the bolt.

While there are other objects which are completely fulfilled by the present structure, the main objects have been herein set forth as well as the preferred embodiment of the invention, but it will be understood that many changes may be made without departing from the spirit and scope of the invention as claimed.

What I claim as new is:

1. In combination with a door, a lock, a shiftable bolt for the lock, an inner knob, a latch swingingly positioned adjacent the inner knob, pivoted engaging hooks upon the said bolt, a slidable plate upon said bolt adapted for withdrawing the said hooks when slidably moved upon the bolt, and a ward upon said inner knob operatively engageable with the said plate and bolt and operable upon turning the inner knob for retracting the bolt when the latch is in one position.

2. In combination with a door, a lock, a shiftable bolt for the lock, an inner knob, a latch swingingly positioned adjacent the inner knob, pivoted engaging hooks upon the said bolt, a slidable plate upon said bolt adapted for withdrawing the said hooks when slidably moved upon the bolt, a ward upon said inner knob operatively engageable with the said plate and bolt and operable upon turning the inner knob for retracting the bolt when the latch is in one position, a projecting lug upon said bolt, and a shiftable stop operable by said latch in the line of movement of said lug and adapted for preventing a retraction of the bolt when the latch is in another position.

3. A lock comprising a shiftable bolt, an inner and an outer knob, a swinging latch adjacent the inner knob, normally projecting engaging hooks carried by the said bolt, a depressing plate for the said hooks slidably carried by the said bolt, an actuator operatively connected to the said plate and having a side notch therein, a lug rigidly connected to the said latch and positioned within the said notch of the actuator during a shifting movement of the said lug and thereby operably connected to the said bolt for

shifting the same when the latch is swung to one extreme limit of its movement.

4. A lock comprising a casing, a shiftable bolt within said casing, an outer knob, operative connections between the said knob and bolt, normally projected spring pressed hooks carried by said bolt, underlying bolt locking members independently shiftable transversely of and located adjacent the said bolt, engaging flanges on the said bolt locking members having edge notches, hooks carried by the said bolt adapted for alining with the said edge notches when the said locking members are in their releasing positions, push button means adjacent the said outer knob, and shiftable means operable by said push buttons and engageable with said locking members for shifting the latter to their said inoperative positions.

20 5. A lock comprising a casing, a shiftable bolt within said casing, an outer knob, operative connections between the said knob and bolt, normally projected spring pressed hooks carried by said bolt, bolt locking members independently shiftable transversely of and located adjacent the said bolt, engaging hooks upon said bolt, flanges carried by the said locking members and having edge notches therein adapted for alining with the said hooks when the said locking members are in their releasing positions, push button means adjacent the said outer knob, shiftable means operable by said push buttons and engageable with said locking members for shifting the latter to their said inoperative positions, dog-engaging means and returning means for the said locking members, and dis-engaging means carried by the said bolt and engageably positioned within the plane of the said dog engaging means whereby the said locking members are automatically released upon a retraction of the said bolt.

45 6. A lock comprising a casing, a shiftable bolt within said casing, a projection spring for the said bolt, shiftable engaging hooks upon the said bolt, bolt locking members transversely shiftable adjacent the said bolt, and projecting stop flanges upon the said locking members normally positioned in the path of movement of the said hooks and having notches therein arranged in alinement with the said hooks when the locking members are in their releasing positions.

55 7. A lock comprising a casing, a shiftable bolt within said casing, a projection spring for the said bolt, shiftable engaging hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, separate return springs

for each of the said locking members, and independently successively operable engaging shifters for the said locking members.

8. A lock comprising a casing, a shiftable bolt within said casing, a projection spring 70 for the said bolt, shiftable engaging hooks upon the said bolt, bolt locking members transversely shiftable adjacent the said bolt, projecting stop flanges upon the said locking members normally positioned in the 75 path of movement of the said hooks and having notches arranged in alinement with the said hooks when the locking members are in their releasing positions, separate return springs for each of the said locking 80 members, independently successively operable engaging shifters for the said locking members, return springs for the said shifters, spaced projecting arms upon the said shifters, pivoted rockers engaging the said 85 arms, and push buttons for the said rockers projecting exteriorly of the said casing.

9. A lock comprising a casing, a shiftable bolt within said casing, a projection spring for the said bolt, shiftable engaging hooks 90 upon the said bolt, bolt locking members transversely shiftable adjacent the said bolt, projecting stop flanges upon the said locking members having notches normally positioned in the path of movement of the 95 said hooks and arranged in alinement with the said hooks when the locking members are in their releasing positions, separate return springs for each of the said locking members, independently successively operable engaging shifters for the said locking members, return springs for the said shifters, spaced projecting arms upon the said shifters, pivoted rockers engaging the said arms, push buttons for said rockers projecting exteriorly of the said casing, a bolt retracting 100 knob operatively connected to the said bolt, an adjustable stop within the return path of movement of the said locking members, and engaging shifting means for the said stop 105 positioned at the door edge side of the casing.

10. A lock comprising a casing, a shiftable bolt within said casing, a projection spring for the said bolt, shiftable engaging 115 hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, separate return springs for each of the said locking members, independently successively operable 120 engaging shifters for the said locking members, return springs for the said shifters, spaced projecting arms upon the said shifters, pivoted rockers having their inner ends operatively engaging the said arms, 125 holding the said rockers in their said side 130

and push buttons engaging said rockers and projecting exteriorly of the said casing.

11. A lock comprising a casing, a shiftable bolt within said casing, a projection 5 spring for the said bolt, shiftable engaging hooks upon the said bolt, bolt locking members transversely shiftable adjacent the said bolt, projecting stop flanges upon the said locking members normally positioned in the 10 path of movement of the said hooks and having notches arranged in alinement with the said hooks when the locking members are in their releasing positions, return springs for the said shifters, spaced projecting arms 15 upon the said shifters, pivoted rockers having their inner ends pivotally engaging the said arms, and push buttons projecting exteriorly of the said casing.

12. A lock comprising a casing, a shiftable bolt within said casing, a projection 20 spring for the said bolt, shiftable engaging hooks upon the said bolt, bolt locking members transversely shiftable adjacent the said bolt, projecting stop flanges upon the said locking members normally positioned in the 25 path of movement of the said hooks and having notches arranged in alinement with the said hooks when the locking members are in their releasing positions, a pivoted lever 30 within said casing, an engaging dog for each locking member pivoted to the pivotal end of the said lever, a tapered plate carried by the free end of the said lever, a normally resiliently projected key-hole spindle carried by the said casing, and a projecting lug upon said spindle having a 35 path of movement in the same plane as the said plate when the said dogs are in their engaged positions.

13. A lock comprising a casing, a shiftable bolt within said casing, a projection 40 spring for the said bolt, shiftable engaging hooks upon the said bolt, bolt locking members transversely shiftable adjacent the said bolt, projecting stop flanges upon the said locking members normally positioned in the 45 path of movement of the said hooks and arranged in alinement with the said hooks when the locking members are in their releasing positions, separate return springs for each of the said locking members, independently successively operable 50 engaging shifters for the said locking members, a pivoted lever within said casing, an engaging dog 55 for each locking member, pivoted to the pivotal end of the said lever, a tapered plate carried by the free end of the said lever, a normally resiliently projecting key-hole spindle carried by the said casing, and a 60 projecting lug upon said spindle having a path of movement in the same plane as the said plate when the said dogs are in their engaged positions.

14. A lock comprising a casing, a shiftable bolt within said casing a projection 65

spring for the said bolt, shiftable engaging hooks upon the said bolt, bolt locking members transversely shiftable adjacent the said bolt, projecting stop flanges upon the said locking members having notches normally 70 positioned in the path of movement of the said hooks and arranged in alinement with the said hooks when the locking members are in their releasing positions, separate return springs for each of the said locking 75 members, independently successively operable engaging shifters for the said locking members, return springs for the said shifters, spaced projecting arms upon the said shifters, pivoted rockers engaging the said arms, push buttons engaging said rockers and projecting exteriorly of the said casing, a pivoted lever within said casing, an engaging dog for each locking member pivoted to the pivotal end of the said lever, a tapered 80 plate carried by the free end of the said lever, a normally resiliently projected key-hole spindle carried by the said casing, and a projecting lug upon said spindle having a 85 path of movement in the same plane as the said plate when the said dogs are in their engaged positions.

15. A lock comprising a casing, a shiftable bolt within said casing, a projection 90 spring for the said bolt, shiftable engaging hooks upon the said bolt, bolt locking members transversely shiftable adjacent the said bolt, projecting stop flanges upon the said locking members normally positioned in the 100 path of movement of the said hooks and having notches arranged in alinement with the said hooks when the locking members are in their releasing positions, separate return springs for each of the said locking members, independently successively operable engaging shifters for the said locking members, return springs for the said shifters, spaced projecting arms upon the said shifters, pivoted rockers engaging the said arms, push buttons engaging said rockers projecting exteriorly of the said casing, a bolt retracting knob operatively connected to the said bolt, an adjustable stop within the return path of movement of the said locking members, engaging shifting means for the said stop 105 positioned at the door edge side of the casing, a pivoted lever within said casing, an engaging dog for each locking member pivoted to the pivotal end of the said lever, a tapered plate carried by the free end of the said lever, a normally resiliently projected key-hole spindle carried by the said casing, and a projecting lug upon said spindle having a 110 path of movement in the same plane as the said plate when the said dogs are in their 115 engaged positions.

16. A lock comprising a casing, a shiftable bolt within said casing, a projection spring for the said bolt, shiftable engaging hooks upon the said bolt, bolt-locking mem- 120

bers transversely shiftable adjacent the said bolt, projecting stop flanges upon the said locking members normally positioned in the path of movement of the said hooks and having notches arranged in alinement with the said hooks when the locking members are in their releasing positions, separate return springs for each of the said locking members, independently successively operable 10 engaging shifters for the said locking members, return springs for the said shifters, spaced projecting arms upon the said shifters, pivoted rockers having their inner ends operatively engaging the said arms, 15 push buttons engaging said rockers and projecting exteriorly of the said casing, a pivoted lever within said casing, an engaging dog for each locking member pivoted to the pivotal end of the said lever, a tapered plate 20 carried by the free end of the said lever, a normally resiliently projected key-hole spindle carried by the said casing, and a projecting lug upon said spindle having a path of movement in the same plane as the said 25 plate when the said dogs are in their engaged positions.

17. A lock comprising a casing, a shiftable bolt within said casing, a projection spring for the said bolt, shiftable engaging hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, return springs for the said shifters, spaced projecting arms upon the said shifters, pivoted 35 rockers having their inner ends pivotally engaging the said arms, push buttons engaging said rockers and projecting exteriorly of the said casing, a pivoted lever within said casing, an engaging dog for each locking member pivoted to the pivotal end of the said lever, a tapered plate carried by the free end of the said lever, a normally resiliently projected key-hole spindle carried by the said casing, and a projecting lug upon said spindle having a path of movement in the same plane as the said plate when the said dogs are in their engaged positions.

18. A lock comprising a casing, a shiftable bolt within said casing, a projection spring for the said bolt, shiftable engaging hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, a bracket 55 within said casing, a lever within the cas-

ing and a plate carried by the lever, a key operable slide movably positioned within the said bracket and adapted for engaging the said plate, a pin adjacent the said slide and a key operated hook pivoted to said slide and adapted for engaging the said pin when the said locking members are released. 70

19. A lock comprising a casing, a shiftable bolt within said casing, a projection spring for the said bolt, shiftable engaging hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, separate return springs for each of the said locking members, independently successively operable 80 engaging shifters for the said locking members, a bracket within said casing, a lever within the casing and a plate carried by said lever, a key operable slide movably positioned within the said bracket and adapted for engaging the said plate, a pin adjacent the said slide and a key operated hook pivoted to said slide and adapted for engaging the said pin when the said locking members are released. 90

20. A lock comprising a casing, a shiftable bolt within said casing, a projection spring for the said bolt, shiftable engaging hooks upon the said bolt, bolt locking members transversely shiftable adjacent the said bolt, projecting stop flanges upon the said locking members normally positioned in the path of movement of the said hooks and having notches arranged in alinement with the said hooks when the locking members are in their releasing positions, separate return springs for each of the said locking members, independently successively operable 100 engaging shifters for the said locking members, return springs for the said shifters, spaced projecting arms upon the said shifters, pivoted rockers engaging the said arms, push buttons engaging said rockers and projecting exteriorly of the said casing, a bracket within said casing, a lever within the casing and a plate carried by said lever, a key operable slide movably positioned within the said bracket and adapted for engaging the said plate, a pin adjacent the said slide and a key operated hook pivoted 105 to said slide and adapted for engaging the said pin when the said locking members are released. 110

21. A lock comprising a casing, a shiftable bolt within said casing, a projection spring 125 for the said bolt, shiftable engaging hooks upon the said bolt, bolt locking members transversely shiftable adjacent the said bolt, projecting stop flanges upon the said locking members normally positioned in the path 130

of movement of the said hooks and having notches arranged in alinement with the said hooks when the locking members are in their releasing positions, a pivoted lever 5 within said casing, an engaging dog for each locking member pivoted to the pivotal end of the said lever, a tapered plate carried by the free end of the said lever, a normally resiliently projected key-hole spindle carried by the said casing, a projecting lug upon said spindle having a path of movement in the same plane as the said plate when the said dogs are in their engaged positions, a bracket within the casing, a key 10 operable slide movably positioned within the said bracket and adapted for engaging the said plate, a pin adjacent the said slide and a key operated hook pivoted to said slide and adapted for engaging the said pin when 15 said locking members are released.

22. A lock comprising a casing, a shiftable bolt within said casing, a projection spring for the said bolt, shiftable engaging hooks upon the said bolt, bolt locking members 20 transversely shiftable adjacent the said bolt, projecting stop flanges upon the said locking members having notches normally positioned in alinement with the said hooks when the locking members are in their releasing positions, separate return springs 25 for each of the said locking members, independently successively operable engaging shifters for the said locking members, a pivoted lever within said casing, an engaging dog for each locking member, pivoted to the pivotal end of the said lever, a tapered plate carried by the free end of the said lever, a normally resiliently projected key-hole spindle carried by the said casing, a projecting 30 lug upon said spindle having a path of movement in the same plane as the said plate when the said dogs are in their engaged positions, a bracket within the casing, a key operable slide movably positioned within 35 the said bracket and adapted for engaging the said plate, a pin adjacent the said slide and a key operated hook pivoted to said slide and adapted for engaging the said pin when 40 said locking members are released.

23. A lock comprising a casing, a shiftable bolt within said casing, a projection spring for the said bolt, shiftable engaging hooks upon the said bolt, bolt locking members 45 transversely shiftable adjacent the said bolt, projecting stop flanges upon the said locking members normally positioned in the path of movement of the said hooks and having notches arranged in alinement with the said hooks when the locking members are in their 50 releasing positions, separate return springs 55

for each of the said locking members, independently successively operable engaging shifters for the said locking members, return springs for the said shifters, spaced projecting arms upon the said shifters, pivoted rockers engaging the said arms, push buttons engaging said rockers and projecting exteriorly of the said casing, a pivoted lever within said casing, an engaging dog for each locking member pivoted to the pivotal end of the said lever, a tapered plate carried by the free end of the said lever, a normally resiliently projected key-hole spindle carried by the said casing, a projecting lug upon said spindle having a path of movement in the same plane as the said plate when the said dogs are in their engaged positions, a bracket within the casing, a key operable slide movably positioned within the said bracket and adapted for engaging the said plate, a pin adjacent the said slide and a key-operated hook pivoted to said slide and adapted for engaging the said pin when 60 said locking members are released.

24. A lock comprising a shiftable bolt, shiftable locking members for the said bolt, when projected, releasing shifters for each of the said locking members, push button actuators for each of the said shifters, dog retainers for the said locking members, and key operated controlling means for the said 65 retainers.

25. A lock comprising a shiftable bolt, shiftable locking members for the said bolt, when projected, releasing shifters for each of the said locking members, push button actuators for each of the said shifters, dog retainers for the said locking members, key operated controlling means for the said 70 retainers, and automatically operable retracting means for the said retainers carried by the said bolt and whereby the said retainers are inactive when the bolt is retracted.

26. A lock comprising a shiftable bolt, locking members engageable with said bolt when in its projected position, means for shifting the said locking members to their releasing positions, means for automatically rendering the said releasing means inactive 75 when the bolt is retracted, and key operated means for rendering the said releasing means inactive at will.

In testimony whereof I affix my signature in presence of two witnesses.

LEO TURK.
